PLUMBING FITTING AND FIXTURE

Filed Jan. 10, 1922

UNITED STATES PATENT OFFICE.

JOHN K. PENNINGTON, OF LOS ANGELES, CALIFORNIA.

PLUMBING FITTING AND FIXTURE.

Application filed January 10, 1922. Serial No. 528,193.

To all whom it may concern:

Be it known that I, JOHN K. PENNINGTON, a citizen of the United States, and a resident of the city of Los Angeles, county 5 of Los Angeles, and State of California, have invented certain new and useful Improvements in Plumbing Fittings and Fixtures; and I declare the following to be a full, clear, and accurate disclosure of the 10 same.

Generally speaking, my invention pertains to plumbing fixtures or fittings, and particularly it pertains to cleanout fittings for urinals, toilets, sinks, bath tubs and similar 15 fixtures.

The foremost object of my invention is to provide a fitting attachable to fixtures of the aforementioned character in such a manner that access may be gained to the 20 sewer pipes thereof for the purpose of flushing out or cleaning out sediment which ordinarily gathers therein from time to time; and also to which may be attached a hose or tubing for the purpose of flushing it 25 out with water; each of these operations being accomplished very easily and quickly and without necessitating the cutting or breaking of more or less rigid connection, or in any way dismantling the building 30 or structure in connection with which the fixture and plumbing is used.

The merits of my improvement will be readily discernible from the following detailed description, reference being made 35 therein to the accompanying drawings forming a part thereof, in which the preferred specific embodiment is illustrated; and in which—

Fig. 1 is a front elevation of a portion 40 of a plumbing fixture in connection with which my invention may be used, showing, also in elevation, a housing for my improved fitting; Fig. 2 is a similar view only showing the lower portion thereof in 45 section, as indicated by the line 2—2 of Fig. 3; Fig. 3 is a central vertical longitudinal section taken as indicated by the line 3—3 on Figs. 1 and 2; Fig. 4 is an enlarged section of one of the screw plugs 50 illustrated in Figs. 2 and 3; Fig. 5 is a front elevation of the last mentioned plug; Figs. 6 and 7 are side and front elevations, respectively, of another of the screw plugs 55 shown in Figs. 2 and 3.

Referring now to the drawings, the numeral 10 designates generally a fragmentary

portion of a typical urinal or similar fixture; and, while it is to be understood that my invention, as herein disclosed, may be used in connection with any typical fixture 60 of this character, it is herein illustrated and will be described in connection with a urinal of the type commonly mounted upon walls a short distance above the floor surface. 65

The numeral 11 designates the bowl or bottom portion of the urinal bowl, and 12 the discharge or flushing pipe leading therefrom. As in the usual manner the urinal 10 is secured to the wall surface—designated herein by the numeral 13—in any suitable manner, as by means of bolts, (not shown). The bowl portion 11 is open at its front and is separated from the discharge pipe 12 by the wall 14. The pipe 12 may be of any suitable cross sectional configuration and of any suitable downward curvature or configuration desired. The type shown in the drawings, is, however, typical of the construction generally utilized. 80

Ordinarily the discharge pipe 12 is circular in cross sectional configuration and is connected at its lower end to a drain pipe 15 by means of an elbow fitting. In 85 place of this elbow fitting or connection I substitute my improved clean out fitting— generally designated by the numeral 16—to the details of which I will presently advert. Ordinarily when the usual elbow 90 connection has been used to join the drain pipe 12 of the urinal 10 and the sewer pipe 15 they have been joined either by a screw threaded connection or by a caulked joint; thereby making a rigid connection 95 and one that can not be easily separated for the purpose of getting into the drain pipes for cleaning them out. Also, when joints of this character have been utilized it has made the assembling and setting up 100 of such fixtures, together with the drain pipes, quite difficult and more or less expensive owing to the fact that the elbow connection must first be screwed into one or the other of these drain pipes and then 105 joined to the other by a caulked or screw threaded connection; and in the latter case requiring that the fixture be placed and connected with the drain pipes at the time they are installed in the wall structure. 110

This is an objectionable feature owing to the fact that it is not usually desired to

install such fixtures until after the building structure has been completed and finished.

With my improved connection these operations are greatly simplified as will herein-after appear. The main portion of the connection 16 comprises a fitting in the form of a T-connection consisting of a body portion 17 and a side outlet 18; the latter being positioned adjacent one end of the former, in the manner shown in Fig. 3. The body portion 17 is externally screw threaded at one end,—as at 17^a—to form a connection with the internally screw threaded end 19 of a sewer pipe 15. Pipes 15 are ordinarily constructed of cast iron: and, while such a screw threaded connection is preferable, either a bolted flanged connection or a caulked joint may be utilized. But, owing to the fact that the portion 17 will ordinarily be connected to the pipe 15 before the fixture 10 is placed, a screw threaded connection at this point will undoubtedly be the simplest and most efficient.

The bottom end 20 of the discharge pipe 12 has an annular flange 21; the transverse face 21^a of which is rabbetted, as at 22. The side outlet 18 of the connection 16 is formed to register with and abut against the face 21^a of the lower end 20 of the pipe 12; the transverse face 18^a of this outlet also being annularly rabbetted, as at 23. These opposed recesses 22 and 23 form seats for the reception and retention of an annular gasket 24, to be clamped and held between these contiguous faces when the members are in place to form a water-tight joint therebetween.

The fitting 16 is held in place, as described, adjacent the lower end 20 of the sewer pipe 12, and the annular gasket 24 is held tightly clamped within the recesses 22 and 23, by means of bolts 25 extending through lugs 26, on either side of the fitting 16, and through a lower wall 27 of the urinal 10. The lugs 26 preferably extend outwardly on either side of the fitting 16, and may be formed integral therewith; and, if it should be desired to simplify the construction of the urinal, the bottom wall 27 thereof, as far as supporting this fitting is concerned, may also be in the form of integral lugs extending outwardly from the lower end 20 of the discharge pipe 12. However, in this particular case, it is desired, for the purpose of presenting a neat and sightly appearance, to enclose the discharge pipe 12 by extending the front wall 28 across and continuing it back on either side to form a junction with or abut against the wall surface 13, or to the plane of its attachment to such wall, by walls 29; these being connected across the bottom by the wall 27.

The outer end 30 of the body portion 17 is annularly flanged and internally screw threaded, as at 31, for the reception of an externally screw threaded plug 32. It is to be noted that the end 31 shows its opening to be considerably larger than the opposite end of this fitting, where the latter end forms its connection with the pipe 15. This is for the purpose of providing as large an opening as possible for cleaning out the pipe; but these proportions may be varied to suit circumstances.

The plug 32 is shown in detail in Figs. 3, 4 and 5; and consists of a main or body portion 33 exteriorly screw threaded, as at 34, to form the screw threaded engagement with the threads 31. An annular flange 35 is formed on the body portion 33 in order that a water-tight joint may be made between this plug and the end 30 of the fitting 16; and, if desired, a gasket may be clamped between this flange and the end face 36 of the end 30. A reduced tubular neck portion 37 is formed on the plug 32, this being interiorly screw threaded for the reception of an exteriorly screw threaded plug 38. The plug 38 is shown in detail in Figs. 3, 6 and 7; being also provided with an annular flange 39 to engage the face 40 of the neck portion 37, to form a water-tight joint, (between which flange and face a gasket may be clamped); and also being provided with a square head 41 which may be engaged by a suitable wrench for adjusting it to the plug 32. In this connection it may be here mentioned that the periphery of the neck portion 37 is also formed to be engaged by a wrench for adjusting it to the portion 17.

The plug 32 has an axial bore or opening 42 extending through a wall 43; this wall 43 being thinner than the depth of the body portion 33 so as to form a recess 44. A conical baffle 45 is supported concentric with the bore 42, upon arms 46, so that its apex 47 will extend into the latter, in the manner shown in Figs. 3 and 4, and its base will be substantially in the plane of the inner face of the plug. The object of this arrangement is to enable the plug 38 to be removed and a hose connection screw-threadedly engaged in the neck 37, for the purpose of flushing out the connection 16 and the discharge pipe 15. When such a connection is made with the neck 37, the conical baffle 45 will split the stream of water directed into the fitting and direct it outwardly in diverging streams through the openings 49, between the arms 46, and into contact with the interior of the walls of the portion 17.

The whole of the fitting 16, and the attachment, is enclosed by a cover or casing 50, the configuration of which is clearly shown in Figs. 1, 2 and 3. The bottom 51 is preferably semicircular to enclose the

fitting 16, horizontal walls 52 extending outwardly therefrom and forming junctures with vertical side walls 53. A front wall 54 extends across and joins the walls 51, 52 and 53, leaving the top and back of the casing open. A channel 55 is formed in the bottom wall 27, of the urinal 10, in the manner shown, for the reception of the upper edges 56 and 57, of the walls 53 and 54, respectively. The casing 50 is held supported in place, in the manner shown, by the extension of bolts 25 so as to extend through the horizontal walls 52 and receive nuts 58.

In the operation and use of my improved clean-out connection, it is clear that the connection proper may be secured to the discharge pipe 15, in either of the manners stated, at the time the rough plumbing is put into the building structure; and also that, owing to the character of connection between this member and the urinal or other fixture, the latter may be attached at any time merely by bolting the portion 17 adjacent the end 20, of the discharge pipe 12, by means of the bolts 25 passing through the wall 27 and the lugs 26. The casing 50 may then be attached to enclose this fitting, by its adjustment to the lower end of the urinal 10, and the attachment of the nuts 58 to the extended ends of the bolts 25, after passing them through the walls 52.

When it is desired to clean or flush out the sewer pipes the casing 50 is first removed by removal of the nuts 58; after which the screw plug 38 may be removed and a hose connection made with the internal threads 48 for flushing out the interior of body portion 17 and the sewer pipe 16. This is a very simple operation and can be done in a very few minutes without disturbing anything but the cover 50 and the plug 38. In case the cleaning to be done cannot be accomplished by the removal of the plug 38 and the attachment of a hose connection to the neck 37, in the manner hereinbefore described, the plug 32 (without removing the plug 38) may be removed from the end 30, of the body portion 17, leaving a much larger opening for access to the body portion 17 and the sewer pipe 15, and also the lower end 20 of the discharge pipe 12. Any of these operations are very simple and can be accomplished without breaking any permanent connections or causing any particular inconvenience; and this cleaning out may be done at a very slight expense.

While I have herein described a preferred specific embodiment of my invention, it is nevertheless to be understood that I reserve the right to make any modifications or changes in structure which will properly come within the scope of the appended claims.

Having described a preferred embodiment of my invention, I claim:

1. In a clean-out connection for a plumbing fixture, the combination of a body portion in the form of a T-connection, means for securing the side inlet of said connection to the discharge pipe of the urinal, means for securing one end of said body portion to a discharge pipe, and a removable member in the opposite end of said portion for gaining access thereto, said removable member comprising a plug, a secondary plug carried by said plug removable to make a hose connection therewith, and means in said first mentioned plug to split and spread a stream of water passing therethrough. 80

2. In a clean-out connection for a plumbing fixture, the combination of a body portion in the form of a T-connection, means for securing the side inlet of said connection to the discharge pipe of the urinal, means for securing one end of said body portion to a discharge pipe, and a removable member in the opposite end of said portion for gaining access thereto, said removable member comprising a plug, a neck carried by said plug, a secondary plug removably secured to said neck and removable to make a hose connection therewith, and a baffle member in said first mentioned plug concentric with said neck to split a stream of water and direct it against the walls of said body member. 90

3. In a clean-out connection for a plumbing fixture, the combination of a body portion in the form of a T-connection, means for securing the side inlet of said connection to the discharge pipe of the urinal, means for securing one end of said body portion to a discharge pipe, and a removable member in the opposite end of said portion for gaining access thereto, said removable member comprising a plug, a neck carried by said plug, and concentric therewith, a secondary plug removably secured to said neck and removable to make a hose connection therewith, and a conical baffle member in said first mentioned plug concentric with said neck to split a stream of water and direct it against the walls of said body member. 100

4. In a clean-out connection for a plumbing fixture, the combination of a body portion in the form of a T-connection, means for securing the side inlet of said connection to the discharge pipe of the urinal, means for securing one end of said body portion to a discharge pipe, and a removable member in the opposite end of said portion for gaining access thereto, said removable member comprising a plug, a neck carried by said plug, a secondary plug removably secured to said neck, and removable to make a hose connection therewith, and a conical baffle in said first mentioned 110

plug concentric with said neck and positioned with its apex towards said neck, to split a stream of water passing therethrough and direct it against the walls of said body member.

5. In a clean-out connection for a plumbing fixture, the combination of a body in the form of a T-connection having one opening adapted for connection to the urinal or 10 the like, another to discharge pipe, and a

removable member closing the third opening, said member having a hose connection opening therethrough and having a spreader to spread a stream of water passing through its said opening.

15

In witness that I claim the foregoing I have hereunto subscribed my name this 20th day of December, 1921.

JOHN K. PENNINGTON
